(57) **CLAIM**

We claim the ornamental design for a closure for a container,
as shown and described.

DESCRIPTION

FIG. 1 is a top perspective view of an embodiment of the
claimed design;

FIG. 2 is another top perspective view of the claimed design of FIG. 1;

FIG. 3 is another top perspective view of the claimed design of FIG. 1;

FIG. 4 is a top plan view of the claimed design of FIG. 1;

FIG. 5 is a bottom plan view of the claimed design of FIG. 1;

FIG. 6 is a first elevation view of the claimed design of FIG. 1;

FIG. 7 is a second elevation view of the claimed design of FIG. 1;

FIG. 8 is a third elevation view of the claimed design of FIG. 1;

FIG. 9 is a top perspective view of another embodiment of the claimed design;

FIG. 10 is another top perspective view of the claimed design of FIG. 9;

FIG. 11 is another top perspective view of the claimed design of FIG. 9;

FIG. 12 is a top plan view of the claimed design of FIG. 9 in a first position of use;

FIG. 13 is a second top plan view of the claimed design of FIG. 9 in a second position of use;

FIG. 14 is a third top plan view of the claimed design of FIG. 9 in a third position of use;

FIG. 15 is a bottom plan view of the claimed design of FIG. 12;

FIG. 16 is a second bottom plan view of the claimed design of FIG. 13;

FIG. 17 is a third bottom plan view of the claimed design of FIG. 14;

FIG. 18 is a first elevation view of the claimed design of FIG. 9;

FIG. 19 is a second elevation view of the claimed design of FIG. 9; and,

FIG. 20 is a third elevation view of the claimed design of FIG. 9.

The broken lines in the drawings depict environmental subject matter only and form no part of the claimed design.
